UNITED STATES PATENT OFFICE.

GEORGE H. CHAPPELL, OF NEW YORK, N. Y., ASSIGNOR OF ONE HUNDRED AND TWENTY-SEVEN TWO-HUNDREDTHS TO JULIUS M. HEYMAN, OF SAME PLACE, AND THEODORE F. BOURNE, OF CLIFTON, NEW YORK.

BALANCED STEAM-VALVE.

SPECIFICATION forming part of Letters Patent No. 443,450, dated December 23, 1890.

Application filed June 30, 1890. Serial No. 357,216. (No model.)

To all whom it may concern:

Be it known that I, GEORGE H. CHAPPELL, a resident of New York city, New York, have invented certain new and useful Improvements in Balanced Steam-Valves, of which the following is a specification.

The object of my invention is to provide a steam-valve that will be perfectly balanced under all steam-pressures, in which the parts will be strong and durable and not liable to get out of order, wherein friction will be reduced to a minimum, and any wear on the parts will be automatically taken up, and a steam-tight fit be automatically effected.

15 The invention consists in the details of improvement and the combinations of parts, that will be more fully hereinafter set forth, and then pointed out in the claims.

Reference is to be had to the accompanying drawings, forming part of this specification, wherein—

Figure 1 is a vertical longitudinal section through a steam cylinder and chest, showing my valve in cross-section. Fig. 2 is a vertical longitudinal section, enlarged, through the valve on the plane of the line $x x$, Fig. 3. Fig. 3 is a longitudinal section, enlarged, on the plane of the line $y y$, Fig. 2. Fig. 4 is an enlarged side view of a spring of the valve. 30 Fig. 5 is an edge view of the same. Fig. 6 is a vertical cross-section on the plane of the line $z z$, Fig. 4; and Fig. 7 is a sectional view of the steam chest and valve, showing a modification.

35 In the accompanying drawings, the letter A indicates the steam-chest, which is to be connected to a steam-cylinder B. (See Fig. 1.)

D is the steam-valve within the steam-chest A, said valve extending entirely across the steam-chest from the side a to the side b , and fitting at its ends snugly against said sides, but being wholly free and disconnected from the walls of the steam-chest throughout its length, so that steam can entirely envelop it between its ends. (See Figs. 1 and 2.) By this means the steam-pressure is the same on all sides of the valve and it has no seat to be pressed against by the steam, the steam being prevented from passing between the ends of 45 the valve and the sides $a b$ of the chest A.

The sides or walls $a b$ of the steam-chest A have inlet-ports $d e$ and an exhaust-port f , said ports communicating with ports $g h i$ in the bottom of the chest A. The ports g and i connect with the supply-ports $j l$ of the steam-cylinder B, while the port h connects with the exhaust-port m of the cylinder. (See Fig. 1.) The ports d and e are alternately covered and uncovered by the valve D, and the valve D is preferably made cylindrical with perfectly flat ends that come against the flat sides $a b$ of the chest A, whereby a tight fit between the valve and the sides $a b$ of the chest is insured, while the steam encircling the valve does not interfere with its free and easy movement.

The inlet-ports d and e I preferably make in the arc of a circle, (see Fig. 1,) their concavities facing each other, so that as the cylindrical valve is moved to uncover a port it will uncover a large area at the beginning of the stroke, and then gradually uncover more, whereby a large amount of steam is quickly admitted to the cylinder at the commencement of the stroke of the valve and piston. 70 By having the port curved a larger port can be used without increasing the stroke of the valve.

I prefer to place friction-rollers $n n$ on the under side of the valve D, which rollers ride on the bottom of the valve-chest, (see Fig. 2,) but the friction at that part is at a minimum, the rollers only having to support the weight of the valve, as the steam between the bottom of the chest A and the under side of the valve counteracts any downward pressure on the valve, thereby putting the valve in equilibrium.

o is the steam-inlet pipe connected to the chest A.

90 The valve D is made longitudinally extensible, and for this purpose is made in two sections E F, passing one within the other. (See Fig. 2.) The section F is hollow and the section E fits snugly within it, the inner end of the section F coming against an annular flange G on the outer end of the section E, the outside diameter of the flange G being the same as the outside diameter of the section F, so that no shoulders will be formed 95 100

on the outside of the valve D. The outer end of the section F is also hollowed out, as at p, to form a passage for the exhaust-steam. The section E is also hollow from end to end, so that steam can pass freely through the interior of the valve, which also materially assists in balancing it, also giving the exhaust a free passage, enabling it to quickly escape, as the hollow part of the valve D always comes over the exhaust-ports f, thereby enabling them to communicate with the inlet-ports at the proper time. The outer end of the section E is also hollowed at q similarly to p. The transverse diameter of the valve D is greater than the length of the ports d e f, so that said ports will always be covered throughout their length. (See Fig. 2.)

The outer ends of the sections E and F of the valve D should be always firmly and snugly held against the sides a b of the steam-chest, and in order to effectually accomplish this and to automatically take up any wear at the end of the valve I form one or more (preferably three or four) passages r in the inner end of the section F, which leads to the flange G on the section E. (See Fig. 2.) The passages r communicate by side passages s in the walls of the valve D with the interior of the chest A, so that steam can enter the passages r and press against the flange G of the section E, thereby moving the sections E F of the valve in opposite directions and holding them against the sides a b of the chest A. The transverse area of the steam-passages r will be proportioned to the maximum steam-pressure to be applied to the valve, so that the ends of the valve will be held against the seats a b with sufficient pressure to insure a tight and lasting fit without such a pressure as would make the valve hard to reciprocate by forcing it against a seat. To keep the steam properly in position in the passages r, I place a tube t in each of said passages, which tubes project into corresponding recesses u in the flange G of the section E, so that when the flange G and section E become slightly separated (say through wear at the ends of the valve) the steam will be properly guided to keep the valve-sections properly spread. By this means the wear at the ends of the valve will be automatically taken up and a steam-tight fit be effected automatically and always insured.

In order to firmly and securely connect the valve-rod H with the valve D, I place a sleeve I around said valve, which sleeve fits tightly on the valve and may be shrunk on the same, if desired. The sleeve I carries a boss J, to which the valve-rod H may be connected by screw-thumbs or otherwise. The sleeve I covers the joint v between the flange G of the section E and the inner end of the section F, so as to prevent steam passing therein. Apertures w are provided in the sleeve I, which register with the passages s to permit steam to enter said passages through said apertures. (See Fig. 2.) The sleeve I preferably extends

nearly the entire length of the valve D and permits the sections to slide one on the other, as necessary.

To keep the two sections E and F of the valve D firmly together, while also permitting longitudinal movement on each other, and to compensate for any wear between them, I place one or more springs L between the sections E F, as shown. Each of these springs L is sunk in a recess a² in the outer side of the section E between the two sections E and F, as shown. Said springs have an outward tendency and press against the inner wall of the section F. Said springs fit snugly at their sides against the sides of the recesses a². Said springs I prefer to construct double—that is to say, one spring within another—and I arrange them as follows, as more clearly shown in Figs. 4 and 6: b² is an inner band-like spring adapted to encircle the section E, said spring being of such a width as to fit tightly against the sides of the recess a². Said spring is made eccentric—that is to say, tapers gradually from its center toward its ends, as in Fig. 4—whereby the desired elasticity combined with strength is derived. d² e² are two parallel spring-bands placed side by side and encircling the spring b². (See Fig. 6.) The ends of the springs d² e² break joints, and also break joints with the ends of the spring b². (See Fig. 5.) By this means the expansion and contraction of the several parts making up the main spring L are evenly regulated. By means of this improved spring the sections E and F of the valve are permitted a proper amount of movement upon each other, while a steam-tight fit is effected between said sections.

The springs L are arranged near opposite ends of the sections E and F, whereby the sections are held in proper relative positions.

A steam - valve constructed as above set forth will be found perfectly balanced under all steam-pressures, as it has no seat to be pressed against by the steam. As it is completely enveloped by steam on all sides between its ends, the pressure will be even on all sides, and thereby the valve will be balanced. Very little power will be required to reciprocate this balanced valve, and therefore a great saving of fuel and wear and tear will be effected. If any wear takes place at the ends of the valve, the steam in the passages r will press the sections outward to take up the wear, and the sections will be held against the sides of the chest with sufficient pressure to make a tight fit without increasing friction.

Of course the ports d and e could be shaped otherwise than in the arc of a circle, as in Fig. 1. For instance, they could be rectangular, as in Fig. 7, in which case the ends of the valve would be also rectangular to properly cover the ports.

I do not herein claim the curved ports, as they are claimed in an application filed by me on October 1, 1890, Serial No. 366,756.

Having now described my invention, what I claim is—

1. A valve composed of two hollow sections, one fitting within the other, one of said sections having a steam-passage that communicates at one end with the exterior of said valve and at its other end leads to the other section, whereby the sections will be moved outwardly relatively to each other by the steam in said passage, substantially as described. 10

2. A valve composed of two hollow sections, one fitting within the other, one of said sections having a steam-passage communicating with the exterior of the valve, a tube in said passage, and a recess in the opposite section, into which said tube projects, whereby steam in said passage and tube acts to press said sections apart, substantially as described. 15

3. A steam-chest having ports on opposite sides *a* *b* and longitudinal ports connecting said ports on the sides, combined with a valve within said chest and extending across the interior of said chest from side to side, the sides of said valve being wholly free from the 20 walls of the chest, said valve being composed of two sections fitting one within the other, and a steam-passage in one section leading to the other section, whereby the ends of the valve will be kept pressed against the sides of 25 the steam-chest, substantially as described.

4. A valve composed of two hollow sections, one fitting within the other, combined with a sleeve *I*, encircling said valve to keep steam from entering between said sections, and with 30 the valve-rod connected to said sleeves, substantially as described.

5. A valve composed of two sections fitting one within the other, the inner section having a flange *G*, a steam-passage in said outer section leading from the outer wall of said sec- 35

tion inwardly to the flange *G* to cause steam to press said sections apart, combined with a sleeve *I*, encircling said valve to cover the joint between said sections, and with the aperture *w* in said sleeve that registers with said steam- 45 passage, substantially as described.

6. A valve composed of two hollow sections fitting one within the other and having a passage entirely through them, combined with a steam-chest, within which said valve fits, and 50 with rollers *n*, carried by said valve and resting on a side of the chest, said valve being entirely surrounded by steam between its ends, while its ends fit against the sides of the chest, substantially as described. 55

7. A valve composed of two hollow sections fitting one within the other, combined with a spring between said sections, substantially as described.

8. A valve composed of two sections fitting one within the other, one of said sections having a recess situated between said sections, combined with a spring in said recess, substantially as described. 60

9. A valve composed of two sections fitting one within the other, and a recess *a*² in one of said sections, combined with a spring in said recess, said spring being composed of an inner spring-band *b*² and another spring-band 65 encircling the inner spring, substantially as 70 described.

In testimony that I claim the foregoing as my invention I have signed my name in presence of two witnesses this 28th day of June, 1890.

GEORGE H. CHAPPELL.
